WILFRID G. CHAUSSÉ, OF DETROIT, MICHIGAN, ASSIGNOR TO CHAUSSÉ MANUFACTURING COMPANY, OF DETROIT, MICHIGAN, A CORPORATION OF MICHIGAN.

ASPHALT-HEATER.

1,295,694.

Specification of Letters Patent. Patented Feb. 25, 1919.

Application filed November 25, 1916. Serial No. 133,324.

To all whom it may concern:

Be it known that I, WILFRID G. CHAUSSÉ, a subject of the King of Great Britain and Ireland, residing at Detroit, in the county 5 of Wayne and State of Michigan, have invented certain new and useful Improvements in Asphalt-Heaters, of which the following is a full, clear, and exact specification.

10 This invention relates to improvements in asphalt heaters. This invention relates particularly to portable heaters designed to apply an intense heat to the surface of an asphalt pavement to melt and burn away 15 the top surface thereof in connection with the resurfacing of the pavement.

The principal object of my invention is to provide a portable heater having a hood carrying burners and confining and directing 20 the heat and flame from the burners upon the surface of the pavement, said hood being so carried and supported from the main frame of the apparatus that it may be lifted vertically a short distance to facilitate the shifting of the apparatus from one 25 section of pavement to another. A further object of my invention is to provide simple, compact and easily operable means for lifting the hood vertically and for supporting 30 it relative to the main frame of the apparatus. Still a further object of my invention is to support the hood from one side of the main frame of the apparatus so that the main frame and the fuel tanks carried 35 thereby are entirely to one side of the hood. This facilitates the use of the apparatus close to street car tracks and prevents injury to it due to an accidental blow from some projecting portion of a passing car.

40 Further objects, and objects relating to economies of operation and details of construction, will definitely appear from the detailed description to follow.

I accomplish the objects of my invention 45 by the devices and means described in the following specification. My invention is clearly defined and pointed out in the appended claims.

50 A structure, constituting a preferred embodiment of my invention is illustrated in the accompanying drawings, forming part of this specification, in which:

Figure I is a top plan view of a structure embodying my invention.

Fig. II is a view in end elevation showing 55 the hood lifted vertically a short distance from the surface of the pavement.

Fig. III is a detail, sectional view taken on the line 3—3 of Fig. I.

Fig. IV is a detail, sectional view taken 60 on the line 4—4 of Fig. II.

In the drawings, similar reference numerals refer to similar parts throughout the several views and the sectional views are taken looking in the direction of the little arrows 65 at the ends of the section lines.

Considering the numbered parts of the drawing, my improved asphalt heater comprises a main frame 10, which is supported on the springs 11 carried by the axle 12 on 70 which the wheels 13 are mounted. The frame 10 is so mounted relative to the wheels that one side of the frame extends laterally beyond the axle as clearly shown in Fig. II. The fuel tanks 14 are carried by the main 75 frame 10 resting on the cross members 16 and held in place by the straps 15. The fuel tanks are mounted on the side of the frame opposite that on which the hood is supported so that their weight tends to counter- 80 balance the weight of the hood, and its supporting parts. An air pump 17 is mounted on one corner of the frame and connected by pipes 18 with each fuel tank so that an air pressure may be maintained in said tanks. 85 A gage 19 is provided to indicate the pressure in the tanks. Valves 20 are provided in the pipes 18 so that either of the tanks may be cut off from the air pump. A tongue 21 is connected to the frame 10 by 90 means of which the apparatus may be hitched behind an automobile or other vehicle and conveyed from place to place.

The upright members 22 are fastened intermediate their ends to one side of the frame 10 and securely braced in that position by the braces 23 and 24 with the lower ends of said upright members extending a considerable distance below the plane of the frame 10. The movable upright members 100 25 are held in parallelism with the first-mentioned upright members and are so supported as to be slideable relative thereto. Yokes 26 embrace each pair of upright

members and are secured to the slidable members 25 by bolts 27. The bolts 28 carried by the yokes 26 hold the uprights 22 and 25 in parallelism while permitting their 5 sliding movement relative to each other. Pulleys 29 are journaled on the upper end of each upright member 22 and a pulley 30 is journaled on each of the slidable uprights 25 intermediate its ends. Flexible connecting members, such as a chain or cable, are fastened to the corners of the frame 10, pass around pulleys 30, up and over pulleys 29, and are fastened to and wound around shaft 32 which is journaled in brackets 38 carried 10 by the frame 10. A handle 34 is provided for rotating the shaft 32 and a ratchet wheel 35 is fixed on said shaft in position to be engaged by the pawl 36 which is pivotally mounted on the frame at 37. 15 Brackets 38 are secured to the lower ends of the slidable members 25 and these brackets are pivotally connected with the adjacent ends of the cross members 39 of the hood 40, so that the hood is hinged to 20 the ends of the slidable uprights 25. Flexible members 55 are connected to the upper ends of members 25 and to the hood at 56, the length of said flexible members being such that, when they are extended, the hood 25 is supported in a horizontal plane. A cross member 57 connects the upper ends of the fixed uprights 22 and braces them and hooks 35 are carried by said cross member in position to engage one of the longitudinal members 41 of the hood structure to hold and support the hood in vertical position. The hood is engaged with said hooks by swinging it upwardly from the position shown in 30 Fig. II to the vertical position and then releasing shaft 32 and lowering the slidable members 25 and the hood until hooks 58 engage the bar 41. This is the position in 40 which the hood is supported when the heater is to be moved for considerable distances from one piece of work to another. 45 The hood 40 comprises the side wall 42 and the top 43 all supported by the framework comprising the cross members 39 and the longitudinal bars 41. A plurality of 50 burners 44 extend through one end of the side wall 42, said burners being partly supported by the bar 45 connected by the bars 46 with the frame work of the hood. Each burner is connected with the main fuel 55 supply line 49 through the pipes 47 each of which has a valve 48 so that any one of the burners can be cut off. The main fuel supply line 49 is connected with pipe 51 through the union 50 which is such as to 60 permit of the movement of the hood relative to the frame. The pipe 51 is connected by the flexible tube 52 with the pipes 53 leading to the fuel tank 14. Each pipe 53 has a valve 54 so that either tank can 65 be shut off and fuel for the burners drawn

from but one of the tanks. This arrangement of duplicate fuel tanks and connections is important since as fast as one tank is emptied the burners can be connected with the other tank and the other tank refilled. 70

The hood is deeper on the side nearest the frame than on the outer side and the burners are arranged in a plane parallel to the top of the hood. This tends to deflect the heat and direct it on to the surface of the pavement so that a very intense flame is directed thereagainst. 75

From the description of the parts given above, the operation should be very readily understood. The burners 44 are preferably 80

of a type using hydrocarbon fuel and are connected with the fuel tanks 14 carried by the frame 10. The frame 10 is supported on the springs which is a feature of 85

practical advantage since it adds materially to the life of the apparatus which is sometimes drawn over very rough streets. The hood 40 is carried by the slidable uprights 25 and may be raised or lowered vertically 90 by the simultaneous sliding movement of the uprights 25 relative to the fixed uprights 22. In Fig. II, the hood is shown raised. When it is located over a section of paving, the surface of which is to be 95 removed, the pawl 36 is moved out of engagement with the ratchet 35 and the shaft 32 allowed to rotate paying out the flexible cables 31 so that the hood is lowered by a vertical movement until it rests on the surface of the pavement. When it is de-

sired to move to a new section of the pavement, the shaft 32 is rotated so as to wind cables 31 thereon lifting uprights 25 and hood 40 vertically. When it is necessary to move the heater for a considerable distance, as from one job to another, the hood is 100 swung upwardly, on its pivotal connections with brackets 38, until it extends in a vertical plane. The uprights 25 and hood 40 are then lowered by releasing shaft 32 until the hooks 58 engage one of the longitudinal bars 41 of the hood framework. 105

It will be seen that all of the supporting framework of the apparatus is to one side of the hood. This permits the use of the heater close to street car tracks since the hood, which of course is nearest to the track, is low and there is little likelihood of injury to the apparatus due to a blow from some projecting portion of a street car. I 110

have already pointed out the fact that the fuel tanks are so arranged on the frame as to counterbalance the hood thus tending to balance the whole apparatus. 115

I am aware that this particular embodiment of my invention, here shown and described, is susceptible of considerable variation without departing from the spirit of my invention, and, therefore, I desire to claim my invention broadly as indicated by 120

125 130

the appended claims. I have found, however, that this embodiment is desirable from many standpoints and, therefore, I wish to claim it specifically, as well as broadly, 5 as indicated by the appended claims.

Having thus described my invention, what I claim as new and desire to secure by Letters Patent is:

1. A heater of the class described comprising the combination of a frame; transporting wheels therefor; a fuel tank carried by and extending longitudinally of said frame to one side of the center thereof; fixed uprights secured to the opposite side of said frame intermediate their ends; uprights held in parallelism with and slidable relative to said fixed uprights; a shaft journaled on said frame and extending longitudinally thereof; releasable means for preventing the 10 rotation of said shaft; a pulley journaled on the upper end of each fixed upright; a pulley journaled on each slidable upright intermediate its ends; a flexible member for each pair of uprights connected at one end 15 to said frame and at the other end to said shaft and passing over the first mentioned pulley and around the last mentioned pulley; a hood hinged to the lower ends of said slid- 20 able uprights and supported thereby in a substantially horizontal plane; burners carried by said hood; and flexible connections between said burners and said tank.
2. A heater of the class described comprising the combination of a frame; transporting wheels therefor; a fuel tank, carried by and extending longitudinally of said frame; fixed uprights, secured to the side of said frame intermediate their ends; uprights held in parallelism with and slidable relative to 25 said fixed uprights; a shaft, journaled on said frame and extending longitudinally thereof; releasable means for preventing the rotation of said shaft; a pulley journaled on the upper end of each fixed upright; a pulley journaled on each slidable upright intermediate its ends; a flexible member for 30 each pair of uprights, connected at one end to said frame and at the other end of said shaft and working on said pulleys; a hood hinged to the lower ends of said slid- 35 able uprights and supported thereby in a substantially horizontal plane; a burner carried by said hood; and connections between said burner and said tank.
3. A heater of the class described comprising the combination of a frame; transporting wheels therefor; a fuel tank carried by said frame; fixed uprights, secured to said frame intermediate their ends; uprights held in parallelism with and slidable relative to 40 said fixed uprights; a shaft, journaled on said frame and extending longitudinally thereof; releasable means for preventing the rotation of said shaft; a pulley journaled on the upper end of each fixed upright; a pulley journaled on each slidable upright intermediate its ends; a flexible member for 45 each pair of uprights, connected at one end to said frame and at the other end of said shaft and working on said pulleys; a hood, 50 hinged to the lower ends of said slidable uprights and supported thereby in a substantially horizontal plane; burners, carried by said hood; and flexible connections between said burners and said tank.
4. A heater of the class described comprising the combination of a frame; transporting wheels therefor; a fuel tank carried by said frame; fixed uprights, secured to said frame intermediate their ends; uprights held in parallelism with and slidable relative to 55 said fixed uprights; a shaft, journaled on said frame and extending longitudinally thereof; releasable means for preventing the rotation of said shaft; a pulley journaled on the upper end of each fixed upright; a pulley journaled on each slidable upright intermediate its ends; a flexible member for 60 each pair of uprights, connected at one end to said frame and at the other end of said shaft and working on said pulleys; a hood hinged to the lower ends of said slidable uprights and supported thereby in a substantially horizontal plane; a burner carried by said hood; and connections between said burner and said tank.
5. A heater of the class described comprising the combination of a frame; transporting wheels therefor; a fuel tank carried by said frame; fixed uprights secured to said frame intermediate their ends; uprights held in parallelism with and slidable relative to 65 said fixed uprights; a rotatable shaft upon the frame, a hoisting mechanism connected therewith for moving said slidable uprights vertically relative to said fixed uprights; a hood hinged to the lower ends of said slidable uprights and supported thereby in a substantially horizontal plane; a burner carried by said hood; and connections between said burner and said tank.
6. A heater of the class described comprising the combination of a frame; transporting wheels therefor; a fuel tank carried by said frame; uprights supported by said frame and movable vertically with reference thereto; a hoisting mechanism for effecting 70 vertical movement of said uprights; a hood hinged to the lower ends of said uprights and supported thereby in a substantially horizontal plane adjacent the surface of the ground; a burner carried by said hood; and connections between said burner and said tank.

In testimony whereof I have signed my name to this specification.

WILFRID G. CHAUSSE.
